UNITED STATES PATENT OFFICE.

ABRAHAM J. BROWN, OF READING, PENNSYLVANIA.

DESIGN FOR A CHARM.

Application filed October 8, 1923. Serial No. 7,430. Term of patent 7 years.

To all whom it may concern:

Be it known that I, ABRAHAM J. BROWN, showing my new design, a citizen of the United States, residing at Reading, in the county of Berks and State of Pennsylvania, have invented a new, original, and ornamental Design for a Charm, of which the following is a specification, reference being had to the accompanying drawing, forming part thereof.

The figure is a plan view of a charm showing my new design.

I claim:

The ornamental design for a charm, as shown.

ABRAHAM J. BROWN.
